UNITED STATES PATENT OFFICE.

HERMAN HERRENBRUCK, OF BELLEVILLE, ILLINOIS, ASSIGNOR TO ORBON STOVE CO.,
OF BELLEVILLE, ILLINOIS, A CORPORATION OF DELAWARE.

DESIGN FOR A COOKING STOVE.

Application filed July 9, 1928. Serial No. 27,416. Term of patent 14 years.

To all whom it may concern:

Be it known that I, HERMAN HERRENBRUCK, a citizen of the United States, residing in Belleville, St. Clair County, and State of Illinois, have invented a new, original, and ornamental Design for Cooking Stove, substantially as shown in the accompanying drawing.

The figure is a perspective view of the article showing my new design.

I claim:

The ornamental design for a cooking stove, substantially as shown.

HERMAN HERRENBRUCK.
